INVENTOR.
Wilhelm Falkenberg
BY
George E. Heinrich
ATTORNEY.

UNITED STATES PATENT OFFICE.

WILHELM FALKENBERG, OF NEW YORK, N. Y., ASSIGNOR TO ALBERT WIELICH, OF NEW YORK, N. Y.

RADIATOR SUN.

Application filed June 6, 1923. Serial No. 643,753.

The present invention relates to improvements in electric heaters, and it is the principal object of the invention to provide a heater with a means for making it useful for medical purposes as a so-called radiator sun.

Another object of the invention is the provision of an electric heater which may readily be changed into a radiator for various colored light rays for medical purposes.

A further object of the invention is the provision of an electric heater combined with means for generating ultraviolet rays for local treatment of patients.

A still further object of the invention is the provision of an apparatus of this kind which may just as well be used with direct as with alternating currents of high frequency.

These and other objects of my invention will become more fully known as the description thereof proceeds, and will then be specifically pointed out in the appended claim.

In the accompanying drawing, forming a material part of this disclosure.

Figure 1 is a side view of my novel apparatus, partly in section, illustrating its use as a heater.

Figure 2 is a fragmentary view similar to Figure 1 illustrating the use of the apparatus as radiator sun for medical purposes.

Figure 3 is a side elevation of my novel sun, partly in section and illustrating its use as a generator for ultraviolet rays for medical purposes.

As illustrated in Figure 1, the apparatus comprises a foot 10 which supports a standard or post 11 to the upper end of which is pivotally secured, a bracket 12 which carries a socket 13 for the reception of the customary heat resistance 14.

A concave mirror or reflector 15 is secured in the usual manner to socket 13 and surrounds the resistance 14.

If the apparatus is to be used for medical purposes as radiator sun, as for instance illustrated in Figure 2, the resistance 14 is replaced by a lamp 16, and the peripheral outer margin of the reflector 15 is provided with four clamps 17 which are adapted to

clamp an exchangeable glass plate 18 against the open front part of the reflector.

The glass plates 18 are varicolored so that rays of various colors are produced by the lamp behind the colored plates.

In case it is desired to generate ultraviolet rays, the apparatus illustrated in Figure 3 is used, in which a holder 19 for the carbons 20 and 21 of an arc light is attached to the socket 13, and lateral shields or baffle plates 22 are provided to avoid a dispersion of the light rays.

A funnel 23 is provided which is attached at one end by means of a bayonet coupling to the front of the reflector. This funnel may be made to receive telescopically in its narrow front part 24, a neck part or tube 25, the outer end of which is closed by a collector lens 26 for the purpose of permitting the use of the apparatus for local radiation of a patient's body. Plug contacts 27 are provided for connecting the apparatus with a source of electricity in the usual manner.

The apparatus can be constructed for use with direct as well as alternating current, in the latter case by simply installing in the foot 10 a high frequency apparatus.

The operation of the device will be perfectly clear from the above description.

The apparatus illustrated in Figure 1 is used as a heater in the ordinary well known manner. If it is desired to use the apparatus for medical purposes, the resistance 14 is replaced by a lamp 16 or by an arc light 19 and glass plates of various colors are conveniently attached to the front part of the reflector, and the funnel 23 is attached to the reflector, and the tube 25 with the collector lens 26 is inserted into the restricted outer end of the funnel.

The apparatus may evidently either be used with any lamp socket and in this case the reflector will be held by the lamp or arc light against the socket.

Having thus described my invention, what I claim as new, and desire to secure by Letters Patent is:

A radiator sun for medical purposes, comprising a stand, a bracket pivotally secured to the upper end of the stand, a socket car-

ried by the bracket, a semi-spherical reflector secured to the socket, clamps removably secured to the marginal edges of the reflector, an approximately semi-spherical member carried by the clamps and closing the open edge of the reflector, the outer surface of said member gradually merging into an elongated neck disposed in line with the

bracket, a tube telescopically arranged in the neck and carrying a collector lens, and 10 a glass plate disposed intermediate the reflector and member.

In testimony whereof I have affixed my signature.

WILHELM FALKENBERG.
